America, a corporation of Delaware

Application March 26, 1942, Serial No. 436,267

5 Claims. (Cl. 179—171)

This invention relates to thermionic amplifiers and, more particularly, to thermionic amplifiers for use in television and video systems requiring a substantially uniform amplification over a very wide band of frequencies.

In television and video systems, as well as other applications, it is often necessary to amplify electrical currents uniformly over a wide band of frequencies extending from very low frequencies to frequencies on the order of five megacycles or more. In certain of the apparatus, as in television, it is also important that the amplified currents retain the same relative phase as the input currents possessed in order to avoid phase distortion. If the amplification of the signalling currents is not uniform, or if phase distortion is present, then the quality of reproduction of the picture is reduced, becoming blurred, distorted, or giving evidence of "ghost" images.

Thermionic amplifiers, due to their inherent plate-to-cathode capacities and grid-to-cathode capacities, militate against uniform amplification over a wide band of frequencies, since this capacity acts as a shunt circuit whose impedance varies inversely with frequency. To overcome the deleterious effects of this shunt capacity in the plate circuit, it has been proposed to use "peaking" circuits in which a small inductance is incorporated so that at the very high frequencies its impedance, when taken together with the impedance of the plate-cathode circuit, tends to resonate and so maintain the load impedance at a reasonably constant figure over a large percentage of the band of frequencies to be amplified. The common types known to the art are the "shunt peaking," the "series peaking," and the combined "shunt and series peaking" circuits. All of these circuits, however, have certain shortcomings. For example, in "shunt peaking" the distributed capacities across the coil and the resistance included in the plate circuit are neglected. In many applications the neglect of these stray capacities results in a response characteristic which deviates widely from that of the calculated response. The same is true in the "series peaking" circuits, where again it is usual to disregard the stray capacities of the plate circuit elements. Ordinarily, if not too many stages are to be used in cascade, reasonably good results may be obtained in television receivers using these priorly known types of high frequency correction circuits. However, in transmitter application, where it is necessary, due to high power present, to use water-cooled resistors, the distributed capacity becomes so large that to ne-

glect it results in unsatisfactory response characteristics of the transmission of video signals.

To overcome the shortcoming of correction circuits known in the prior art, I have found that improved results can be obtained by taking into account the stray capacity of both the inductance and the resistance used in the plate circuit and by suitably proportioning the values of these capacities with respect to the sum of the plate-cathode capacity of the tube, the grid-cathode capacity and stray capacity due to the wiring of the succeeding stage, that it is possible to obtain a response characteristic which will fall off smoothly or monotonically only 1.3% over the entire pass band from a uniform value and in which the delay time of the maximum frequency is held within such a small value that the phase response can be considered substantially linear. These results are obtained by suitably relating the three capacities concerned as well as the value of inductance and resistance and my invention will describe how these parameters must be related.

Accordingly, one of the objects of my invention is to provide a new and improved thermionic amplifier having a superior response and phase characteristic.

Another object of my invention is to provide a thermionic amplifier which is corrected so as to give substantially uniform amplifications at very high frequencies as well as low and moderate frequencies.

Still another object of my invention is to provide a thermionic amplifier having a load circuit comprising a resistance and an inductance connected in series and each of these elements shunted by suitable capacities to provide substantially constant impedance over a wide band of frequencies.

40 Other objects will become apparent upon reading the following detailed description in conjunction with the drawings.

In the drawings, in Figure 1, I have shown a circuit of a thermionic amplifier embodying my invention, using shunt capacities across plate circuit elements;

In Figure 2 I have shown schematically an electrical network which is the equivalent of the plate circuit of the thermionic amplifier shown in Figure 1;

In Figure 3 I have shown a further modification of my invention in which the thermionic amplifier is used to feed a synchronizing separator and video reproducer;

In Figure 4 I have also shown a further em-

bodiment of my invention in which the electrical network of my invention is used in a modulator for a television transmitter;

In Figure 5 there is shown graphically the relationship between certain parameters of the electrical circuit embodied in my network, as well as the time delay as a function of one of the parameters; while

Figure 6 shows a family of response curves as a function of frequency of an amplifier embodying the principles of my invention.

In Figure 1, the thermionic amplifier 3 is fed with input energy to its grid-cathode circuit through the terminals 1. A suitable biasing battery 1 is provided to operate the amplifier on the linear portion of its characteristic. The plate circuit comprises a serially connected load resistor 17 and inductance 13 shunted by condensers 19 and 16 respectively. In addition, there is shown the condenser 11 which represents the plate-cathode capacity of the tube 3 as well as the distributed capacity of the wiring and the grid-cathode capacity of the amplifier 5. The tube 3 is energized by a source of voltage 9 and the tube 5 is energized by input signals from the output circuit of the tube 3 through the condenser 21 and the resistor 23. It is important to note that both the inductance 13 and the resistor 17 are shunted by individual condensers because it is these condensers which make it possible to achieve the improved performance of the amplifier. It is of course of further importance to be sure that the condensers 15, 19, and 11, all bear proper relation to each other and to the inductance and resistance in order that the amplification shall be uniform. To appreciate and to show the relationship between these condensers it is necessary to digress and analyze the electrical network in the plate circuit of the tube 3.

The equivalent network of the tube 3 plate circuit is shown in Figure 2, in which the condenser C is the equivalent of the condenser 11 in Figure 1, while condensers C₁ and C₂ are the equivalent of condensers 15 and 19, respectively, and L and R are the equivalent of the elements 13 and 17, respectively, in Figure 1. It is well known of course that the amplification of a thermionic amplifier whose plate impedance is large compared to the impedance of the plate load circuit is given by the product of the transconductance of the tube and the load impedance. Since the transconductance of the tube is substantially constant, it will be readily noted that constant amplitude as a function of frequency requires that the impedance remain constant, that is to say, that the impedance of the network Z₀ should be substantially constant over the band of frequencies it is desired to amplify. To ascertain the conditions which must be met by the relationship of the parameters shown in the network in order to provide substantially constant impedance, the first step is to express the impedance of the network as a function of frequency.

The impedance Z₀ of the network shown in Figure 2 can be shown to be, in operational form, given by:

$$(1) \quad Z_0 = \frac{R \left[1 + \frac{L}{pR} + p^2 LC_1 + p^2 LC_2 \right]}{1 + pCR + pC_1R + pLC_1 + p^2 LC_1C_2R + p^2 LCC_1R + p^2 LCC_2R}$$

This form of the equation, when solved, provides the reciprocal of the indicial admittance, but since we are interested only in the steady-state

performance, it is somewhat more convenient to find the impedance as a function of the angular velocity. This can be done by substituting j_ω for p. In addition, if we let L=aCR², C₁=bC, C₂=mC, then by substitution and collection of like terms, we can find the ratio of the impedance to the resistance R from the expression:

$$(2) \quad \frac{Z_0}{R} = \frac{[1 - \omega^2 abCR^2 - \omega^2 amC^2 R^2] + j\omega aCR}{(1 - \omega abCR^2 - \omega^2 aC^2 R^2) + j(\omega CR + \omega mCR - \omega^2 abmC^2 R^2 - \omega^2 abC^2 R^2 - \omega^2 amC^2 R^2)}$$

By further substitution of x=ωCR, we derive:

$$(3) \quad \frac{Z_0}{R} = \frac{(1 - abx^2 - amx^2) + j(ax)}{(1 - abx^2 - ax) + j(x + mx - abmx - abx^2 - amx^2)}$$

Rationalizing Equation 3 we obtain Equation 4:

$$(4) \quad \left[\frac{Z_0}{R} \right]^2 = \frac{1 + (a^2 - 2ab - 2am)x^2 + (a^2b^2 + 2abm + a^2m^2)x^4}{1 + (1 - 2ab - 2a + 2m + m^2)x^2 + (ab^2 + 2ab^2 - a^2 - 2abm - 2ab - 2am - 2am^2)x^4 + (a^2b^2m^2 + 2ab^2m^2 + b^2m^2 + 2abm + a^2m^2)x^6}$$

which is now in the form to apply the Tellegen-Verbeck procedure for ascertaining the values of a, b, and m, which will make the squared impedance function given by the Equation 4 a monotonic one.

A monotonic solution is one in which the impedance function changes uniformly without change of sign of the rate of change of the impedance with frequency. In accordance with the method for solving for the values of a, b, and m to give such a monotonic solution, it is necessary that the co-efficients of the same powers of x occurring in the numerator and the denominator be equated, that is to say, that the co-efficient of x² in the numerator is equated to the co-efficient of x² in the denominator, the co-efficient of x⁴ in the numerator is equated to the co-efficient of x⁴ occurring in the denominator, etc., and thus results a series of simultaneous linear equations which, when solved, will give the values of a, b, and m, to render the impedance-squared function of Equation 4, one which has constant value over a prescribed range of frequencies.

The resultant equations are as follows:

$$(5) \quad 1 - 2a - a^2 + m^2 + 2m + 2am = 0$$

$$(6) \quad 2abm + am^2 - 2ab - a + 4bm + 2m + 2b + 2bm^2 + 2m^3 = 0$$

$$(7) \quad b^2m^2 + 2b^2m + 2bm + b^2 + 2bm + m^2 = 0$$

Reducing these equations we obtain:

$$(8) \quad a = -(1-m) \pm \sqrt{2(1+m^2)}$$

$$(9) \quad b = \frac{(1+m)(a - am - 2m)}{2(1+m)^2 - 2a(1-m)}$$

$$(10) \quad m = -\frac{b}{b+1}$$

It will be noted that an explicit solution for obtaining a truly uniform impedance function can not be realized physically since Equation 10 shows that m must have a negative value which would require that the capacity C₂ be negative. Inasmuch as a negative capacity can not be supplied readily, only an approximate solution can be obtained over a range of values in which the range is determined by the fact that if m is made 0, the circuit reduces to a tuned shunt peaking circuit, and if b is made 0, then the circuit reduces to the so-called resistance-capacity "shunt-peaking" circuit. By substituting m equal to 0 in Equations 8 and 9, we find that the values of a and b are 0.414 and 0.353, respectively. By now substituting b equal to 0 in the same equations, we find that a equals 0.736 and m 0.269. Since it is known that the two limiting cases can provide substantially

monotonic solutions, it will be noted m may have a range of values lying between 0 and 0.269. Thus, if we restrict the value of m between these values, we may arbitrarily select m within the range and solve for a and b with the knowledge that any one of these solutions will give a substantially monotonic solution over the required frequency range. A table of values showing the relationship between a , b , and m is shown in the following table:

m	a	b
0.000	0.414	0.353
0.050	0.494	0.271
0.100	0.520	0.197
0.150	0.580	0.134
0.200	0.640	0.072
0.269	0.736	0.000

In Figure 5 the values of a and b have been plotted as a function of m . The significance of this plot is that selecting any value of m , the values of a and b may be immediately determined, which will render the impedance function substantially monotonic.

The response curve of an amplifier utilizing the network shown in Figure 2 is shown in a family of curves in Figure 6, where each curve represents the response for the indicated value of m . There is also shown, in Figure 5, the maximum time delay at the maximum frequency for which substantially uniform amplification is desired as a function of m . It will be noted that as m is made larger the maximum time delay decreases. Although the decrease in maximum time delay with increasing values of m is not a rapid one, it affords the designer some flexibility in choice of circuit constants so that, depending upon whether or not the cutoff of the amplifier or the phase delay of the amplifier is important for the specific problem at hand, the value of m may be chosen which will give the optimum solution. The time of transmission is obtained by noting that the tangent of phase angle is equal to the ratio of the imaginary portion of the impedance function to the real portion of the impedance function. From this expression, the phase angle can be written as the anti-tangent of the ratio. Differentiating the phase angle with respect to the variable x will then result in an expression which gives the time of transmission, since by definition this time of transmission is equal to the rate of change of phase with respect to the variable x . The time delay is equal to the difference between the times of transmission at the top frequency and minimum frequency. The results of the maximum time delay for the type of circuit chosen are incorporated in the curve shown in Figure 5.

The network shown in Figure 2 becomes particularly useful in certain television applications, of which the circuit shown in Figure 3 is exemplary. In Figure 3 there is shown a video amplifier circuit such as is useful in the television receiver. The thermionic amplifier 33 is fed with the detected combined video and synchronizing signals at the terminals 31. The output circuit comprising the lumped stray capacities 35 and the load resistor 41 with its peaking coil 37 and capacities 43 and 39, respectively, feeds both the video reproducer from the output terminals 48 and the synchronizing signal separator 45 which is connected across the resistor 41. The output of the synchronizing separator 75

feeds the reproducer's synchronizing circuit 47, which may be of any of the types well known in the art, to supply the synchronized sweep frequencies for the video reproducer. It will be noted that the synchronizing separator 45 is not connected across the terminals 48 as is done in conventional receivers. The reason for this is that when the synchronizing separator is fed in parallel with the video reproducer, the combined stray capacity becomes approximately twice as large as that of the stray capacity of the video reproducer itself. Under these conditions, therefore, the value of the resistance 41 would have to be reduced to approximately one half the value to obtain the desired band width of frequencies. Consequently, the amplifier would have its efficiency reduced.

However, by placing the synchronizing separator across the resistor 41, the total stray capacity 35 is reduced, since the input capacity of the synchronizing separator 45 may actually supply the required capacity across the resistor, that is to say, the input capacity of the synchronizing separator supplies the capacity 43. It is possible to use this type of connection because the band width required for the synchronizing signal is considerably smaller than that required for the video amplifier. One may therefore use a much larger value of resistance in the circuit shown in Figure 3 and consequently achieve much higher gain and greater efficiency from the amplifier 33.

Another example of where this circuit is particularly useful is shown in Figure 4, where the network of the type shown in Figure 2 is embodied in a modulator stage of a television transmitter. In Figure 4 the signals to modulate the carrier frequency are applied to the terminals 51 of the modulator tube 53 whose plate circuit 40 comprises the inductance 57 and the water-cooled resistor 59. The output of the tube 53 feeds through a condenser 67 which is supplied with a biasing rectifier 69 to the push-pull stage of the transmitter. Coils 71 are radio frequency coils to prevent the carrier frequency from getting back into the modulator stage. The carrier frequency is supplied to a balanced input circuit comprising the inductance 75 and the condensers 73 and 71 and is tuned by the condenser 79. The push-pull tubes 81 and 83 consequently have their grids outside the radio frequency in push-pull, while the modulator merely serves to shift the operation point on the characteristic of the two tubes so as to vary the amplitude of the radiated radio frequency energy in accordance with the video signals supplied in the terminals 51. In a transmitter using water-cooled coil and resistance, the distributed capacity may run on the order of 25 micro-micro farads across the resistor and as high as 125 micro-micro farads across the coil. With these values it will be readily appreciated that the distributed capacity across the inductance and across the resistance can not be neglected if satisfactory performance is to be obtained. By choosing proper value of m and taking into account the value of stray capacity 55 enough additional capacity 65 can be had across the resistor to fulfill the conditions of the equations given above or those prescribed by the graph shown in Figure 5. Improved operation is provided by taking into account the distributed capacities across the plate load elements of the modulator. This type of circuit is particularly useful because it does away with the necessity of using "building-out" sections which

were necessary in the conventionally designed types of modulators.

It will be appreciated that the applications shown in Figures 3 and 4 are by way of example only and are not exclusive of use of this type of circuit in other portions of television systems or in amplifiers wherever a wide band of frequencies must be transmitted and in which the amplitude response must be substantially constant over the band of frequencies.

Various alterations and modifications of the present invention may become apparent to those skilled in the art and it is desirable that any and all such modifications and alterations be considered within the purview of the present invention except as limited by the hereinafter appended claims.

Having now described my invention, what I claim is:

1. A video amplifier comprising a thermionic amplifier having at least a cathode, control electrode, and an anode, and a load circuit comprising an inductance shunted by a condenser connected in series with a resistance shunted by a condenser connected in the cathode-anode circuit, the values of the inductance, resistance and condensers being such that the impedance of the load circuit remains substantially constant over a wide frequency range.

2. A video amplifier comprising a thermionic amplifier having at least a cathode, control electrode, and an anode, and a circuit comprising an inductance shunted by a condenser connected in series with a resistance shunted by a condenser connected in the cathode-anode circuit, the value of said inductance being chosen proportional to the product of the resistance squared and the distributed capacity between the anode and cathode of the said thermionic amplifier.

3. A video amplifier for amplifying a wide band of frequencies uniformly, said band having a maximum predetermined frequency comprising a thermionic amplifier having at least a cathode, control electrode, and an anode, and a circuit comprising an inductance shunted by a condenser connected in series with a resistance shunted by a condenser connected in the cath-

ode-anode circuit, said resistance having a value inversely proportional to the product of said maximum predetermined frequency and the distributed capacity between the anode and cathode of said thermionic amplifier.

4. A video amplifier for amplifying a side band of frequencies uniformly, said band having a maximum predetermined frequency comprising a thermionic amplifier having at least a cathode, control electrode, and an anode, and a circuit comprising an inductance shunted by a condenser connected in series with a resistance shunted by a condenser connected in the cathode-anode circuit, said resistance having a value inversely proportional to the product of said predetermined maximum frequency and the distributed capacity between the anode and cathode of said thermionic amplifier and the value of said inductance being chosen proportional to the product of the square of the resistance and the distributed capacity between said anode and said cathode.

5. A video amplifier for amplifying a side band of frequencies uniformly, said band having a maximum predetermined frequency comprising a thermionic amplifier having at least a cathode, control electrode, and an anode, and a circuit comprising an inductance shunted by a condenser connected in series with a resistance shunted by a condenser connected in the cathode-anode circuit, said resistance having a value inversely proportional to the product of said maximum predetermined frequency and the distributed capacity between the anode and cathode of said thermionic amplifier, the value of said inductance being chosen proportional to the product of the square of the resistance and the distributed capacity between said anode and said cathode, said capacity shunted across said inductance being proportional to said distributed capacity, said proportionality factor being greater than zero and less than 0.353 and said capacity shunted across said resistor being proportional to said distributed capacity, said proportionality factor being greater than zero and less than 0.269.

ELMER DUDLEY GOODALE.
